Primary Examiner—Wallace R. Burke*Assistant Examiner*—Monica A. Hannon*Attorney, Agent, or Firm*—Rogers, Howell & Haferkamp[57] **CLAIM**

The ornamental design for a combined closet shelf and hanger rod unit, as shown and described.

DESCRIPTION

FIG. 1 is a perspective view of a combined closet shelf and hanger rod unit showing our new design;

FIG. 2 is a top plan view thereof;

FIG. 3 is a front elevational view thereof;

FIG. 4 is a left end elevational view thereof;

FIG. 5 is a right end elevational view thereof;

FIG. 6 is a rear elevational view thereof; and,

FIG. 7 is a bottom plan view thereof.

The shelf unit is shown broken away in the views to indicate indeterminate length.

FIG. 1.FIG. 2.FIG. 3.

FIG. 4.

FIG. 5.

FIG. 6.

FIG. 7.
